Gilchrist, PA(57) **CLAIM**

The ornamental design for an unmanned aerial vehicle, as shown and described.

DESCRIPTION

FIG. 1 is a front perspective view of the unmanned aerial vehicle, according to the present design.

FIG. 2 is a bottom perspective view of the unmanned aerial vehicle, according to the present design.

FIG. 3 is a front side of the unmanned aerial vehicle, according to the present design.

FIG. 4 is a back side view of the unmanned aerial vehicle, according to the present design.

FIG. 5 is a left side view of the unmanned aerial vehicle, according to the present design.

FIG. 6 is a right side view of the unmanned aerial vehicle, according to the present design.

FIG. 7 is a top side view of the unmanned aerial vehicle, according to the present design.

FIG. 8 is a bottom side view of the unmanned aerial vehicle, according to the present design.

FIG. 9 is a top right side perspective view of the unmanned aerial vehicle, according to the present design; and,

FIG. 10 is a bottom left side perspective view of the unmanned aerial vehicle, according to the present design.
